UNITED STATES PATENT OFFICE

EARL W. LITTLE, OF INDIANAPOLIS, INDIANA

DESIGN FOR A BIRD CAGE LATCH

Application filed March 11, 1931. Serial No. 39,029. Term of patent 7 years.

To all whom it may concern:

Be it known that I, EARL W. LITTLE, a citizen of the United States, residing at Indianapolis, in the county of Marion and State of Indiana, have invented a new, original, and ornamental Design for Bird Cage Latch, of which the following is a specification, reference being had to the accompanying drawings, forming part thereof.

Figures 1, 2 and 3 are front, side and rear elevational views respectively, of the bird cage latch, showing my new design.

The latch is a broad beak-like structure, having a comparatively straight top line, having a comb-like part consistent with the beak effect of the design and including a stem and a base.

I claim:

The ornamental design for a bird cage latch, as shown.

EARL W. LITTLE.
